UNITED STATES PATENT OFFICE.

LEE DE FOREST, OF NEW YORK, N. Y., ASSIGNOR TO DE FOREST RADIO TELEPHONE CO.,
A CORPORATION OF NEW YORK.

SPACE TELEPHONY.

1,006,635.

Specification of Letters Patent. Patented Oct. 24, 1911.

Application filed July 8, 1907. Serial No. 382,674.

To all whom it may concern:

Be it known that I, LEE DE FOREST, a citizen of the United States, and a resident of New York, in the county of New York and State of New York, have invented a new and useful Improvement in Space Telephony, of which the following is a specification.

My invention relates to certain novel improvements and discoveries which I have made relating to the art of transmitting signals between two separated points without the use of artificial conductors and it relates particularly to the wireless transmission of vocal or other sounds, including articulate speech.

My invention comprises certain features, parts and combinations thereof which will be hereinafter described and particularly pointed out in the claim.

The drawings which accompany and form a part of this specification represent in diagram several arrangements of apparatus and circuits which have been employed, although it will be understood that I do not limit myself to the particular arrangements therein illustrated inasmuch as many modifications may be made in said apparatus and circuits without departing from the principle of my invention.

In the drawings, Figures 1, 2 and 3 represent space telephone transmitting systems constructed in accordance with the present invention.

In the figures, G is a generator of unidirectional electromotive force herein represented as a direct current dynamo.

G' is a polyphase generator, herein shown as a three-phase generator.

R R are resistances.

C is a condenser.

S is a discharger herein shown as a gap in which an electric arc may be created between suitable electrodes.

S'' is a discharger herein shown as a spark-gap.

S' S' are spark-gaps located in the transmitting antenna and herein shown in the earth connector thereof.

A is an antenna earthed at E.

M is a transformer of which the primary and secondary windings are I₁ and I₂, respectively.

T is a transmitter herein shown as a microphone.

B is a battery.

D D are electromagnets.

In the present known systems of wireless signaling each signal element, as a dot or a dash, is transmitted by a series of oscillations caused by a series of single sparks, 60 the spark series representing different signal elements being separated by a period of time in which there are no sparks. Each of these sparks represents a series of electrical oscillations of high frequency and of 65 decreasing amplitude—that is, the wave train sent out is damped and the rate of damping is greater or less depending on whether the oscillating system at the transmitter is a good radiator or a good resonator. For long distance transmission it is 70 desirable that the transmitting system should combine both qualities—that is, that it should have a very decided period of its own and should still radiate outwardly from 75 its upright wire a considerable amount of energy at every oscillation. In a strongly damped wave train the first few oscillations, while of considerable amplitude, are soon so reduced in amplitude as to be of little 80 value in exciting a receiving antenna or circuit into response. Such wave train therefore has little cumulative exciting effect upon any receiving apparatus. Therefore for the purpose of carrying out the 85 present invention I prefer to use an apparatus which will radiate a substantially continuous or undamped train of waves all of equal amplitude. Such a wave train has, by reason of its persistency, a strong cumulative 90 exciting effect and is therefore capable of producing effects at a far greater distance than is possible from a damped wave train, even if the maximum amplitude of the latter be much greater than that of 95 the former. A receiving system whose natural period of electrical vibration coincides with that of the wave train will ultimately pick up and respond to a weak but persistent wave train by reason of the 100 cumulative effect of said wave train thereon.

In my present invention I make use of a substantially continuous series of waves, or as near an approach to a continuous radiation of waves as is practicable and modify 105 the amplitude of said waves by the action of sound-operated devices in such manner that the amplitude may be varied without interrupting their continuity. Such waves may be modified by various means, some of 110

which are herein described and illustrated in the accompanying drawings.

It has been pointed out by Duddell, Peukert, Guthe, and Simon that if a circuit containing self-induction and capacity be put in shunt around a direct current arc and the resistance of said arc properly adjusted, the arc will give out a musical note, the pitch of which coincides with the frequency of the electrical oscillations in said shunt circuit. It has also been pointed out by Tesla that if said arc be created in an atmosphere containing hydrogen, the operation thereof is made more efficient. It is also known that if a telephone transmitter and battery be suitably associated with the aforesaid arc and its circuit, words spoken in the microphone transmitter will be reproduced and magnified in sound in the arc itself. In the case of a direct current arc shunted by self-induction and capacity and ordinarily spoken of as the "singing-arc," there is an alternating or oscillating current in the shunt circuit which is continuously maintained by means of the direct current of the arc. This is the exact electrical analogue of the acoustic phenomenon where a continuous blast of air maintains a reed in rapid vibration, as in an organ pipe. Where a microphone transmitter is associated with said arc or its circuit, the minute current fluctuations produced in the microphone circuit by the sonorous vibrations of the air accompanying the sounds which affect said microphone may be employed in various ways for varying the amplitude of the currents in said arc or its circuit in accordance with said sounds. We may also employ spark-balls for the purpose of creating practically continuous trains of electrical oscillations, and in either case by using a source of direct current of sufficiently high voltage and by reducing the dimensions of the self-induction and capacity in the shunt circuit, we may obtain for a proper length and resistance of gap the continuous generation of electrical oscillations of sufficiently high frequency to effect the radiation of electromagnetic waves. Such an arrangement applied to wireless telegraphy is shown in Figs. 1 and 2 in which the circuits S C I, are sources of undamped or practically continuous electrical oscillations of high frequency. The oscillations in these circuits may be transmitted to the radiating antenna A in any suitable manner and as shown herein the oscillation transformer M is employed for this purpose. By this arrangement the potential of the direct current source G need be only moderate because the desired high potentials for radiating purposes may be obtained by said transformer in which the ratio of transformation may be as large as desired. The direct current potentials are in no case measures of the potentials exist-

ing in the oscillation circuit since by the resonance effects of the latter, a large increase in electromotive force always is obtained. Where however it is desirable to obtain direct current potentials in excess of those conveniently obtainable from a direct current generator, the arrangement shown in Fig. 3 may be employed.

In Fig. 3, the conductors of the three-phase generator G' are connected to the points 1, 2, 3, which may be inclosed in a suitable vessel 5, and to the star-point o of zero potential through the inductances L₁, L₂, L₃, respectively. If from said star-point a conductor be led to the plate 4, there will be obtained in said conductor a unidirectional current flowing in the direction of the arrow, said current being the resultant of the currents flowing through the vessel 5, which may contain any suitable atmosphere maintained at any desired pressure, from the points to the plate. This resultant unidirectional current will be practically a constant current and of a voltage practically equal to that of the alternating currents delivered by the generator G'. As will be obvious, a transformer may be interposed between the point-and-plate arrangement, which constitutes a polyphase rectifier, and the generator G'. I do not limit myself to the particular form of polyphase rectifier shown in Fig. 3 inasmuch as various other forms may be employed for securing from a high potential polyphase current a unidirectional current of any desired voltage. In the circuit which includes the point o and plate 4 a discharger S'' for the condenser C may be inserted and there will be obtained in this case practically continuous high potential electrical oscillations in the circuit S'' C M', since this is a shunt circuit around the spark gap S'' and contains capacity and inductance, the spark gap S'', being also included in the circuit of the plate 4 and the zero point o, and which carries unidirectional constant current of a voltage practically equal to that of the generator G', as above explained. The point o being the point of zero potential of the polyphase system may be connected to earth and the antenna A may be associated in any suitable manner with the oscillation circuit, the associating means being shown in the present instance as consisting of the auto-transformer M'.

If a continuous wave train produced by the transmitting systems shown in Figs. 1, 2 or 3 impinges upon a receiving antenna and if the amplitudes of said wave trains are varied in any arbitrary manner and at any rate within the limit of audibility or within the limit of response of the diaphragm of a telephone receiver, which is properly associated with an oscillation detector, sounds of corresponding intensities

and rates of vibration will be produced by said telephone receiver. It is therefore only necessary to alter the amplitudes of the waves of the continuous train of waves produced at the transmitting station to correspond with the amplitudes and rates of vibration of the acoustic waves to be transmitted, to bring about reproductions of such acoustic vibrations in the receiver, be these 10 musical tones or human speech.

A convenient means for varying the amplitude of the oscillations produced at the transmitting station without interrupting their continuity, consists as shown in the 15 drawings of two electromagnets D, D placed in proximity to the gaps S or S' and the direction of the common field of force of which is normal to that of each gap.

Current fluctuations produced in the circuit of the battery B and transmitter T produce corresponding changes in the strength of the magnetic field across the gap and such changes in strength of said magnetic field produce corresponding variations in the amplitude of the electrical oscillations created in the circuits of the gaps S or S'. As shown in Fig. 1, the transmitting circuit with its magnets D, D, may be associated with the source of practically continuous electrical oscillations, while as shown in Figs. 2 and 3, it may be associated with a gap S' included in the antenna circuit, preferably in the earth connector thereof where the current is a maximum and where it serves as a resistance, without, however, interrupting the continuity of the oscillations surging back and forth therethrough, the conductivity of such resistance 35 being varied by varying the strength of the magnetic field in which it is placed.

It will be noted that the electrical waves which are depended upon for the transmission from one station to another are not the impulses which are directly produced by the action of the sound waves or the currents in the circuit of the microphone transmitter, but are waves which are produced in a circuit which is distinct from such microphone circuit and are not dependent for their production or primary intensity upon the action of said microphone. Neither is there any necessary relationship between the period of the transmitting impulses and the period of the sound waves. The periods of the sound waves correspond with the periods of the variations in intensity of the transmitted electromagnetic waves. In other words, the rate of vibration of the transmitted waves is wholly distinct from that of the sounds to be transmitted and the amplitude of said waves is varied in accordance with that of said sounds, and the rate of variation of the amplitude of said waves corresponds with the rate of vibration of said sounds.

I claim:

In a space telephone transmitting system, a transmitting antenna, means for developing electrical oscillations therein, spark-electrodes in said antenna, electro-magnets arranged in proximity thereto and a telephone transmitter and source of electrical energy associated with said electromagnets.

In testimony whereof, I have hereunto 75 subscribed my name this 3d day of July, 1907.

LEE DE FOREST.
